MOBILE STORAGE VEHICLE FOR GARDEN TOOLS AND SIMILAR ARTICLES

William S. Clark, 1348 Pacific St., Santa Monica, Calif.
90405, and Daniel C. Clark, 1949 Las Tunas Road,
Santa Barbara, Calif. 93103

Filed July 26, 1966, Ser. No. 3,209

Term of patent 14 years

(Cl. D14—3)

FIG. 1

FIG. 2

FIG. 4

FIG. 3

FIGURE 1 is a side elevational view of the mobile storage vehicle for garden tools and similar articles, showing our new design;

FIGURE 2 is an end elevational view taken from the right side of FIGURE 1;

FIGURE 3 is a side elevational view of the opposite side of FIGURE 1; and

FIGURE 4 is a perspective view.

The garden tools shown in broken lines in FIGURE 4 are included for illustrative purposes only.

We claim:

The ornamental design for a mobile storage vehicle for garden tools and similar articles, substantially as shown and described.
